(57) CLAIM

The ornamental design for an adult amusement device, as shown and described.

DESCRIPTION

FIG. 1 is a perspective view of an adult amusement device, showing my ornamental design;

FIG. 2 is a front elevation view of the adult amusement device of FIG. 1;

FIG. 3 is a rear elevation view of the adult amusement device of FIG. 1;

FIG. 4 is a left side elevation view of the adult amusement device of FIG. 1;

FIG. 5 is a right side elevation view of the adult amusement device of FIG. 1;

FIG. 6 is a top plan view of the adult amusement device of FIG. 1; and,

FIG. 7 is a bottom plan view of the adult amusement device of FIG. 1.

Any broken lines (e.g., for the handle of the adult amusement device) are included for illustration purposes only and form no part of the claimed design.

1 Claim, 4 Drawing Sheets
